The ornamental design for hockey stick shaft, as shown and described.

DESCRIPTION

FIG. 1 is a rear left perspective view showing hockey stick shaft according to our design;

FIG. 2 is a rear elevation view of the hockey stick shaft of FIG. 1, a front elevation view being a mirror image thereof;

FIG. 3 is a right side elevation view of the hockey stick shaft of FIG. 1, a left side elevation view being a mirror image thereof;

FIG. 4 is a bottom plan view of the hockey stick shaft of FIG. 1;

FIG. 5 is a cross-sectional view of the hockey stick shaft taken along the line 5—5 in FIG. 2;

FIG. 6 is a cross-sectional view of the hockey stick shaft taken along the line 6—6 in FIG. 2;

FIG. 7 is a cross-sectional view of the hockey stick shaft taken along the line 7—7 in FIG. 2;

FIG. 8 is a cross-sectional view of the hockey stick shaft taken along the line 8—8 in FIG. 2;

FIG. 9 is a rear left perspective close-up view of the portion of the hockey stick shaft indicated by bracket 9 in FIG. 1;

FIG. 10 is a rear elevation view of the portion of the hockey stick shaft of FIG. 9, a front elevation view being a mirror image thereof;

FIG. 11 is a right side elevation view of the portion of the hockey stick shaft of FIG. 9, a left side elevation view being a mirror image thereof;

FIG. 12 is a rear left perspective close-up view of the portion of the hockey stick shaft indicated by bracket 12 in FIG. 1;

FIG. 13 is a rear elevation view of the portion of the hockey stick shaft of FIG. 12, a front elevation view being a mirror image thereof; and,

FIG. 14 is a right side elevation view of the portion of the hockey stick shaft of FIG. 12, a left side elevation view being a mirror image thereof.

Throughout the Figures, broken lines showing structure and environment (e.g. a typical hockey stick blade) are for illustrative purposes only and form no part of the claimed design. Portions of the hockey stick shaft not shown in the Figures do not form part of the claimed design.
